UNITED STATES PATENT OFFICE.

MERTON W. FLEET, OF NATIONAL, WASHINGTON.

WEED-CUTTER.

1,391,823.

Specification of Letters Patent. Patented Sept. 27, 1921.

Application filed June 15, 1920. Serial No. 389,216.

To all whom it may concern:

Be it known that I, MERTON W. FLEET, a citizen of the United States, and resident of National, county of Lewis, and State of Washington, have invented certain new and useful Improvements in Weed-Cutters, of which the following is a specification.

This invention relates to improvements in weed cutting devices, and more particularly to devices of that character especially adapted for cutting weeds along a railway track; the principal object of the invention being to provide a device for this purpose, comprising weed cutting blades that may be operatively suspended from a locomotive or car truck, and which are equipped with means whereby, one riding in the locomotive may actuate or move the blades into or from cutting position.

It is also an object of the invention to provide a device of this character comprising a pair of blades for cutting weeds between the rails of a track and from which blades are extended laterally to overlie and cut the weeds at the outer sides of the rails. Also, to provide actuating mechanism whereby all the blades may be simultaneously moved, by a single lever, into or from cutting position.

Another object of the invention is to provide a device of the above character that will be relatively inexpensive, easily mounted and operated, and which will very effectively perform the work for which it is intended.

In accomplishing these and other objects of the invention, I have provided the improved details of construction, the preferred forms of which are illustrated in the accompanying drawings, wherein—

Figure 1 is a side elevation of a part of a locomotive, showing a weed cutting device mounted thereon according to the present invention, and shown in raised position.

Fig. 2 is a perspective view of the weed cutting device removed from the locomotive but in cutting position relative to the track.

Referring more in detail to the drawings; 1 and 2, respectively, designate forward and rearward supporting cross bars which may be fixed in any suitable manner to the trucks or frame parts of a locomotive 3, or other car, in such manner as to support the cutter parts, presently described, directly over the track on which the locomotive or car is adapted to travel.

The forward bar 1 is equipped, at its opposite end, with rearwardly extending brack-

ets 4, and revolubly supported therein, cross-wise with respect to the track, is a hanger rod 5 having downturned opposite end portions 6, and a central off-set crank portion 7. 60 The cross bar 2 has down turned sections 8 at its opposite ends provided with a series of paired apertures 9 wherein the horizontal end portions 10 of a hanger member 11 may be pivotally extended; this hanger comprises 65 alined off-set portions 12 which correspond to the two hanger portions 6 of the member 5, and a central off-set portion 13 corresponding to, and which is connected by an actuating rod 14, with the crank portion 7 of the 70 member 5, so that these two hanger members may be actuated together, in their supports, in a pivotal or swinging manner.

Pivots suspended from the lower ends of the downturned ends 6 of the hanger 5, 75 and the corresponding offset portions 12 of the hanger 11, are a pair of cutter blades 15 and 16, which are supported in a horizontal plane with their forward ends at such spaced apart distance that when in cutting position 80 they will be disposed closely to the inside of the track rails 17, and their rearward ends will be overlapped to form a V-shaped cutter. These blades are sharpened on their inner edges and when carried forward will receive 85 the weeds in a sort of wedge formed thereby which is very effective in operation.

Extending laterally and rearwardly from the blades 15 and 16, are cutter blades 18 and 19, each of which is sharpened along 90 its forward side and has an upwardly offset portion 20 which is adapted to overlie the rail at that side and permit the blade or cutter portions to extend closely to the ties. These lateral blades are fixed rigidly to the 95 central blades and are moved therewith into and from cutting position.

One end of the hanger 11 has a laterally turned crank portion 25 to which is attached one end of a connecting rod 26 which at 100 its opposite end is likewise attached to a lever 27 that may be mounted at any position where it can be conveniently operated by one on the locomotive, and which, when moved rearwardly, will actuate the hangers 105 11 and 5, which are connected by the rod 14, in such manner that the blades will be lowered to cutting position, as shown in Fig. 2, and when moved forwardly will actuate the hangers in a manner that will raise the cutter blades from operative position, as they are shown in Fig. 1.

Assuming that the device is so constructed, and mounted, on a locomotive as shown, or on any other type of car, it is apparent that the cutting blades could be moved into or 5 from cutting position by actuation of the lever 27, and when in cutting position, and the locomotive traveling at a moderate speed, will very effectively cut the weeds between and at the outside of the rails.

10 It is also apparent that by adjustment of the lever 27, the cutter blades may be adjusted to cut close to the ties or at a higher level, or could be moved to their nonfunctional position. Such a device would be 15 effective in operation, could be made durable, and would be relatively inexpensive in its construction and operation.

What I claim as new, is:

1. The combination with frame members 20 of a railway car or the like mounted to travel on parallel rails, of a weed-cutting device carried by said frame comprising a pair of rearwardly converging cutter blades sharpened along their inner edges, and means 25 operable from the car for actuating the blades to and from cutting position between the said rails.

2. The combination with frame members

of a railway car or the like mounted to travel upon parallel rails, of a weed cutting 30 device comprising a pair of rearwardly converging cutting blades suspended beneath said frame members to operate between the said rails, laterally extending blades fixed to the first named blades to 35 overlie and extend beyond the said rails and means operable from the car for moving the blades to and from cutting position.

3. The combination with frame members 40 of a railway car or the like, mounted to travel upon parallel rails, of a weed cutting device comprising forward and rearward swingingly mounted hangers, a pair of rearwardly converging cutter blades supported at their opposite ends by said hangers for 45 operation between the rails on which the car is mounted, laterally extending blades fixed to the first named blades to overlie and extend beyond the said rails, a lever pivotally attached to the car, and rod fixed to said lever and to one of said hangers whereby the latter may be actuated to swing the blades to and from cutting position.

Signed at Seattle, King county, Washington, this 26th day of May, 1920.

MERTON W. FLEET.
